US00D524992S

(12) **United States Design Patent** (10) **Patent No.:** **US D524,992 S**
Belin et al. (45) **Date of Patent:** **** Jul. 11, 2006**

(54) **PAIR OF WELDING HELMET VISOR FLANGES**

(75) Inventors: **Rutger Belin**, Leksand (SE); **Lennart C. Fredriksson**, Basvagen (SE); **Jonas D. Fridholm**, Bromma (SE); **Oskar E. Juhlin**, Gustavsberg (SE); **Niklas Lilenthal**, Djura (SE); **Kjell I. Mases**, Gagnef (SE); **David Craaord**, Bromma (SE)

(73) Assignee: **3M Innovative Properties Company**, St. Paul, MN (US)

(**) Term: **14 Years**

(21) Appl. No.: **29/236,038**

(22) Filed: **Aug. 9, 2005**

(51) LOC (8) Cl. **29-02**

(52) U.S. Cl. **D29/122**

Primary Examiner—Ruth McInroy

(74) Attorney, Agent, or Firm—Karl G. Henson

(57) **CLAIM**

The ornamental design for a pair of welding helmet visor flanges, as shown and described.

DESCRIPTION

FIG. 1 is a perspective view, showing the new design for a pair of welding helmet visor flanges;

FIG. 2 is a left side view, the right side view being a mirror image thereof;

FIG. 3 is a top view thereof;

FIG. 4 is a front view thereof;

FIG. 5 is a bottom view thereof; and,

FIG. 6 is a rear view thereof.

The broken lines form no part of the claimed design, and the shading is provided to illustrate contour only and is not an indication of texture, gloss, etc.

1 Claim, 4 Drawing Sheets
